UNITED STATES PATENT OFFICE.

WILLIAM M. HEPBURN, OF TOLEDO, OHIO, ASSIGNOR TO THE SURFACE COMBUSTION COMPANY, INC., OF TOLEDO, OHIO, A CORPORATION OF NEW YORK.

TUNNEL-TYPE GAS BURNER.

Application filed October 28, 1927. Serial No. 229,428.

This invention relates to improvements in gas burners and more particularly to gas burners of the type having refractory tunnels within which combustion occurs, an example 5 of this type being shown in patent to Willson 1,289,992.

This invention has among its objects to increase the usefulness of gas burners of the tunnel type by providing a bank of burner 10 tiles which will automatically adjust itself to differences in expansion and contraction; to make the individual sections of the burner bank of such form that they may be easily nested to present a compact burner surface, 15 and in general to reduce the cost of manufacture and upkeep of tunnel type burners and to increase the efficiency of the burners.

Referring to the drawings wherein the preferred form of burner is shown, Fig. 1 is in 20 part an elevational and in part a sectional view of the improved burner; Fig. 2 is a plan view of a sufficient portion of the burner surface to illustrate the nature of the invention, and Fig. 3 is a perspective view of one of the 25 elements of the burner construction.

In the drawings, 10 indicates a gaseous mixture supply chamber to which is connected at any suitable point a gaseous mixture supply 30 pipe 12. The upper side of the chamber serves as a base plate 14 for supporting a multiplicity of tubular refractory combustion tunnels in a manner hereinafter specified.

On the upper side of the base plate 14 are formed a series of cylindrical bosses 16 each 35 of which is provided with an aperture 18. These apertures constitute spuds or nozzles through which the explosive mixture passes from the supply chamber for burning. Centered on each boss is a tubular combustion 40 tunnel or tile 20 of larger internal diameter than the diameter of said apertures 18.

The combustion tunnels are made from refractory material and are preferably hexagonal in cross section. The hexagonal form is 45 preferred because it allows the greatest number of tunnels per unit area with uniform spacing between the tunnels. In accordance with this invention the tunnels are supported on the base plate 14 out of individual contact 50 with each other or, to put the matter in another way, the tunnels are loosely nested. By

loosely nesting the tunnels, expansion and contraction may occur without destructive stresses being set up such as would occur if a plurality of tunnels were formed in a solid refractory body. Another important result attained by making the combustion tunnels as individual members and supporting them in loosely nested position is that in case of breakage of a tunnel from one cause or another, replacement can be made by merely lifting out the damaged tunnel and replacing it by a new one. It will now be seen that by making the tunnels as individual members I accomplish a number of important results without in any manner detracting from the efficiency of the burner, that is to say, by making the tunnels as individual units and by nesting them loosely the liability of breakage of the tunnels under expansion and contraction of the burner 70 surface as a whole is completely eliminated and in case of breakage of a tunnel from one cause or another, replacement by a new tunnel is only a matter of lifting out the damaged tunnel and inserting a new one. Other advantages from a manufacturing standpoint 75 will be readily apparent to those skilled in the art. For example in making burners of different sizes, aside from providing the proper size of burner base plate, it is only a matter of using the requisite number of tunnels from a stock supply.

By providing a relatively great number of relatively small capacity combustion tunnels instead of fewer tunnels of large capacity 85 where explosive gaseous mixtures are to be burned, a very desirable degree of flexibility 90 of operation of the burner may be had without danger of back flash into the supply chamber.

The ratio between the length of the tunnel and the internal diameter thereof is an important factor in the successful operation of the burner. I have found that the best results are obtained where the ratio between the 95 length and diameter of the tunnel are as four is to one. Thus for a tunnel of one-half inch diameter the length of the tunnel should be about two inches. Considerable variation may be made from these relative sizes but 100 taking into consideration all the various factors said ratio is the most desirable.

What is claimed is:

In a gas burner for burning a preformed mixture of gas and air, the combination of a mixture supply chamber having a flat wall 5 which is provided with a plurality of feed ports therethrough, a bed of refractory combustion tunnels abutting on said wall, the

tunnels being arranged one in axial alignment with each feed port and out of lateral contact with each other, the walls of said tunnels 10 being relatively thick.

In testimony whereof I affix my signature.

WILLIAM M. HEPBURN.
